INVENTOR,

Joseph D. Bell

UNITED STATES PATENT OFFICE

2,328,255

CHAIR BED

Joseph D. Bell, San Francisco, Calif.

Original application May 16, 1940, Serial No. 335,593. Divided and this application December 29, 1942, Serial No. 470,479 1/2

2 Claims.

(Cl. 5—47)

The present invention relates to improvements in chair beds, and is a division of my co-pending application, Serial Number 335,593, filed May 16, 1940, which latter application was a continuation-in-part of my application, Serial Number 309,855, filed December 18, 1939.

The general object of the invention is to provide improvements in a chair bed constructed in such a manner that it may be conveniently operated by an occupant between chair and bed positions by the mere shifting of weight of the body of the occupant.

More particularly it is proposed in the present invention, to arrange the chair bed in such a manner that it may be changed from a chair into a bed without causing the rear edge to project rearwardly very far beyond its original rear plane. This feature allows a chair of the character described to be placed with its top rear edge relatively close to the wall of a room and to be changed into a bed without the necessity of moving the chair bed as a whole.

It is further proposed in the present invention to provide a chair bed comprising a main supporting frame and a movable frame structure including rigid back and seat sections hinged together and means for supporting the frame structure on the main frame with freedom of floating movement between chair and bed positions.

Another object of my invention is to provide a peculiar link mechanism as a support for a movable frame structure, the said mechanism allowing the back section to rock on an intermediate support when the upper end of the back is pressed downward and, at the same time, exerting a forward pull on the back section, whereby the entire movable frame is pulled forward toward bed position.

A further object of the invention is to provide an improved supporting means for the seat causing the latter to advance and rise to a position of alignment with the back section as the latter is tilted and lowered into horizontal position.

Further objects of my invention will appear as the specification proceeds and the novel features of my invention will be fully set forth in the claims hereto attached.

The preferred forms of my invention are illustrated in the accompanying drawing, in which:

Figure 1 shows a longitudinal section through one form of chair bed, in chair position;

Figure 2, a longitudinal section through the same chair bed, in bed position; and

Figure 3, a longitudinal section, similar to that

of Figure 2, of a slightly modified form of chair bed.

While I have shown only the preferred forms of my invention, I wish to have it understood that various changes and modifications may be made within the scope of the claims hereto attached, without departing from the spirit of the invention.

Referring to the drawing in detail, Figure 1 shows a main frame 1 comprising side members 2 adapted to serve as arm rests for an occupant of the chair, and end members 3 and 4, one in the rear of the frame and the other in the front thereof.

The rear member is shown as being considerably higher than the front member, and the frame is preferably supported on short legs 5.

The movable frame structure 6 comprises a back frame 7 and a seat frame 8, the two frames being hinged together, as at 9, for swinging movement between angular and aligned positions. Suitable upholstery 10 covers the entire movable frame structure from end to end and moves with the same, the upholstery being constructed to furnish a perfectly smooth surface in bed position and to throw an inwardly turned fold, as at 11, in chair position.

The structure of the upholstery is substantially the same as that disclosed in my co-pending application, Serial Number 309,855, above referred to.

For supporting the movable frame structure, I provide two links 35 and 36. The link 35 is pivoted to the bottom of the main frame, near the rear wall, as at 37, and to an intermediate portion of the back, by the pivot 38.

The link 36 is pivoted to the frame at its upper end, as at 39, and has its lower end pivoted to a bracket 40 projecting downwardly from the rear edge of the seat, as at 41. Shoes 42 are provided for raising the seat as it is moved forward.

In operation, when the upper end of the back is pressed downward, the back rocks on the pivot 38, and the hinge 9 moves forward. This forward movement of the hinge is accompanied by a similar forward movement of the bracket 40 and its pivot 41. Since the latter pivot has to follow the path of an arc about the center 39, with the link 36 serving as radius, it will move forward on a wider circle than would normally be described by the hinge 9 rocking on the pivot 38.

Inasmuch as the hinge 9 has to follow the path of the pin 41, it is apparent that it will imme-

diately exert a forward pull on the pivot 38, and thus cause the entire unit to move forward as soon as the tilting movement begins. This forward movement in immediate response to the tilting movement compensates, to some extent at least for the normal rearward swing of the top of the back, so that, as a result, there is only a very small amount of actual rearward swing to the top of the back.

If, therefore, the back of the chair is located relatively close to the wall of the room, the converting movement may be effected without first moving the entire chair bed away from the wall.

During the converting movement, the shoe on the seat rides on the front wall 4 of the chair bed, and raises the seat to a position of alignment with the back when the latter drops into horizontal position, as shown in Figure 2.

In the latter position, the back and the seat are supported on the rear and front members 3 and 4 of the main frame, and the links cooperate in holding the movable frame unit in horizontal position.

It will be noted that the pivot 39 is almost vertically above the pivot 37, and that the free end of the link 36 is forward of the free end of the link 35 in both positions.

To reverse the movement, it is only necessary to lift the projecting end of the back section, which will automatically cause the different parts to resume the position of Figure 1.

The form shown in Figure 3 differs from the first form principally in the shape of the main frame which is made of steel pipe, comprising floor members 12, standards 13 rising from the rear ends thereof, standards 14 rising from the front ends thereof, and connecting members 15

and 16 forming front and rear supports for the mattress units in horizontal position. The bracket 40 is directly secured to one of the hinge leaves by means of bolts 43 passing through the seat frame.

It should be understood that throughout the specification, where the term "link" has been used in the singular, this has been done for the sake of simplicity, and that, in reality, the same link mechanism is used on both sides of the chair bed.

I claim:

1. In a chair bed, a main frame, a back and a seat having a hinge connecting the same, two links, each having one end pivoted to the main frame near the rear thereof, one near the bottom and the other near the top and substantially vertically above the former, a pivotal connection between the other end of the first link and an intermediate portion of the back, a bracket projecting downwardly from the seat, and a pivotal connection between the second end of the second link and the bracket.

2. In a chair bed, a main frame, a back and a seat section hingedly connected together to form a foldable unit, two links, each having one end pivoted to the main frame near the rear thereof, one near the bottom and the other near the top and substantially vertically above the former, a pivotal connection between the other end of the first link and the intermediate portion of the back section of the unit and a pivotal connection between the second end of the second link and the unit adjacent the hinge thereof, the said unit being operable by means of the said links to travel bodily forward on the main frame with the tilting of the said back.

JOSEPH D. BELL.
